G. M. Kendall,
Cracker Machine,
Patented May 3, 1833.

May 3, 1833

George M. Hinman Rochester N.Y.

S. B. & Co. Invent.

The invention referred to in the Letters Patent and making part of the same, containing a description in the words of the late George M. Hinman himself of his improvement in the machine for cutting corduroy.

Be it known that, George M. Hinman of the town of Rochester in the County of Genesee and State of New York have made an improvement in the machine for cutting corduroy which is described as follows.

This machine is composed of a frame for supporting the machinery a sliding board on which the rollers are cast, rollers and band to move the sliding board a cast iron frame, a head piece containing the cutters bear-stirrup, and spiral springs for operating the cutters, also for preparing the web, crank handle or wheel before preparing the machine. The frame marked A in the annexed drawing, is constructed by fastening together two side pieces two end pieces and four plates of such size and strength as to support the other parts of the machine. The plates being bent back in the top of the side pieces of the frame to receive the sliding board.

The sliding board C is made as the inside of the frame between the plates and of the length of the frame. Two rollers are placed across the frame between the side pieces & under the sliding board. A band D fastened to the under side of the sliding board is passed around these rollers by which the board is moved backwards & forwards & cast iron frame B composed of two upright standards & a top plate is erected in the center of the frame & to which it is fastened by screw bolts, on the inside of each standard is a slot to receive the head piece.

The head piece containing the cutters is cast with a groove in each end to slide in the side iron standards on the under side of the head piece are fitted as many holes as there are cutters to be used and into which the cutters are firmly fixed. In the center of each cutter and the head piece is made a hole to receive a set of

to the lower end of which there is attached a collar working in the cutter the upper end is fastened to the top plate of the frame. The locking lines are inserted into the cutting in the usual manner. A movable frame composed of two parts & a cap is fastened on the top of the base frame.

The four side pieces of this frame are numerous bars of iron projecting hanging two openings in the top plate of the cast iron frame. In the center of the cap piece of the movable frame is a small standard K. The lever L is made of iron of suitable length & strength to operate the cutter and extends across the frame having one end attached to an upright post M by a pin to which it turns and is connected with the movable frame by an other pin N hanging from the top of the small standard L and low. The other end of the lever extends over the side of the machine having a strip shape O attached to it by which it is operated. Spiral springs P are placed around the post of the movable frame, one end of each spring resting on the plate of the cast iron frame & the other end bearing against the inner side of the cap piece of the movable frame.

The roller Q for rolling the dough is upright thickup placed across the top of the frame near the cutter to guide the dough in the table to you. It is graduated by steps and spiral springs S to any thickup of dough required. One of the graders projects sufficiently far to receive a crank handle T and crank handle V. This long crank works into another crank which turns the end of the grader of one of the rollers carry ing the lame and sliding board. The operation of the machine is as follows.

The dough is prepared on the brake; it is then laid upon the sliding board; the crank handle tumed which brings forward the sliding board with the dough under the rollers where it is rolled to paper thickup; it is then carried forward under the cutter; the operator feet is put into the steps at the end of the lever and pushed down which brings down the end of the lever and with it the movable frame & cutter; The cutter are then set and locked; the first is then run and the movable frame returns to its former position by the action of the spiral springs; at the same time the cutter are disengaged from the cutter by the falling on the rest of the cutter.

In this manner the operation is continued. The sides and top of the trough are
planed in the ordinary way. A portion of one of the rods is working into
a crack in the under side of the movable board, may be substituted for the
yellow wood board to close the seam.

What I claim as my invention in the
type described, is in the application of the spiral spring lever used, being
operated in the manner above described in cutting troughs.

In testimony whereof I have set my hand.

My name this 29 day of April 1830.
